BÉLA SCHAEFER, OF FRANKFORT-ON-THE-MAIN, GERMANY, ASSIGNOR TO THE FIRM OF HARTMANN & BRAUN A.-G., OF FRANKFORT-ON-THE-MAIN, GERMANY.

VAPOR ELECTRIC APPARATUS.

1,097,473.

Specification of Letters Patent.

Patented May 19, 1914.

Application filed February 25, 1913. Serial No. 750,663.

To all whom it may concern:

- Be it known that I, BÉLA SCHAEFER, a citizen of the German Empire, and residing at Frankfort - on - the - Main, Province of 5 Hesse-Nassau, in the Kingdom of Prussia, Germany, have invented certain new and useful Improvements in Vapor Electric Apparatus, of which the following is a specification.
- 10 This invention relates to vapor electric apparatus and has for its object to provide means for condensing the metal vapors rising from the cathode.
- In vapor electric apparatus, and more particularly in mercury vapor rectifiers, two facts are of special importance; the arrangement of the electrodes with relation to each other and the condensing chamber. As 15 a matter of fact the anodes are the less exposed to arcing the more they are withdrawn from the deleterious influence of the cathode blast. On the other hand one has early recognized the usefulness of a condensing chamber for the purpose of maintaining the vapor pressure in as low a state 20 as possible. Such facts, however, were hitherto considered only in the construction of rectifiers for small output having glass bulbs, while rectifiers for large output are 25 wanting of such contrivances and hence are insufficient as regards capacity. In mercury vapor rectifiers of this type the vacuum vessel is preferably of a cylindrical form, allowing the introduction of a plurality of 30 anodes through the upper cover and also permitting their arrangement in the form of a ring. However, there is a difficulty still to be obviated which will be more perceptible as a higher output is required. In 35 cylindrical vacuum vessels of this type, the enlargement of their capacity for the purpose of obtaining a condensation chamber of sufficient dimensions, can only be attained either by increasing the diameter of the vessel or by the elongation of the axis of the vessel. Neither of these arrangements appear to give satisfactory results since wide cylinders of relatively short axial extension 40 require unnecessarily heavy end-plates the tightening of which is connected with great difficulties (see Fig. 1); on the other hand long cylinders having a small diameter have the disadvantage of the distance from the 45 anodes to the cathode being too long or, if the anodes are arranged in the proximity of

the cathode, the leading-in conductors will be too long so that they are heated to such an extent as to prevent their own heat to be conducted in a sufficient manner. It is obvious from Fig. 2 also that the insulation 60 of such long conductors is connected with difficulties.

The present invention has for its object to do away with such inconveniences by suitable arrangements which meet all the requirements above referred to.

The invention will be readily understood by reference to the following description taken in connection with the accompanying drawing which, by way of example, illustrates various embodiments my invention 70 may assume in practice.

Figures 1 and 2 illustrate the extremes of the cases above referred to. Fig. 3, 4 and 5 show sectional views of my invention.

Referring more particularly to Fig. 3, *g* is a vacuum vessel consisting essentially of two chambers *f* and *h*. The upper chamber *f* serves as condensing chamber, while the lower one *h* is the vapor chamber. Both 80 parts are connected by means of the ring-shaped member *d* which, as it appears from the drawing, serves at the same time for supporting the electrodes. By inserting this intermediate member at a suitable distance 85 from the cathode *h* it is attained that, notwithstanding the anodes being arranged close to the cathode, the whole vacuum vessel may be extended in vertical direction as far as required. Even in the case of a great 90 number of anodes, *a* being used the common support *d* may be made of a single turned piece which may be easily handled.

Through the anode support being formed as an independent massive ring the designing 95 as well as the manufacture of the individual parts is highly simplified. The outlines of this ring need not be traced out in revolution, it being only required that, in choosing suitable diameters for the same, 100 the total weight of the vessel, the main parts of which may consist of thin sheet iron, be not essentially increased. Besides the small distance of the electrodes from one another the main advantage of this arrangement is 105 that the anodes are exposed to the cooling effect of the support *d*.

Preferably the ring *d* is rigidly connected with a condensing chamber *f*, *f. e.* by welding, but detachable from the vapor 110

chamber h at z , so that the latter chamber can be opened for inspection when required. The starting or auxiliary electrodes e_1, e_2 serve for starting and maintaining the cathode h if separate maintenance is required at all. By means of a directing screen l the individual anode-streams are collected immediately above the cathode.

Fig. 4 illustrates by way of example another form which my invention may assume in practice and wherein the space left on the inner side of the support is relatively small so that the condensing chamber f above the orifice o must be widened. The water-jacket casings k_1, k_2 with tubular connections r_1, r_2, r_3 are provided to insure an efficient water-cooling of the whole surface of the rectifier.

In the foregoing figures vacuum-vessels are shown having exclusively the anodes introduced in vertical direction. The invention may, however, equally well be employed in connection with rectifiers having the electrodes led-in horizontally or in a plane inclined to the horizontal. Fig. 5 shows such an arrangement which is especially adapted for use in connection with currents of high intensity and low voltage.

A special advantage of my invention is that the individual parts of the vacuum vessel, especially the walls, may be made of glass, thus offering the possibility of a perfect insulation of the cathode.

Now, what I claim is:—

1. In metal vapor apparatus, the combination of a vapor chamber, a condensing chamber, a ring shaped member, connecting the vapor chamber and the condensing chamber, electrodes supported in said ring member and arranged in a circle.

2. In metal vapor apparatus, the combination, of a vapor chamber, a condensing chamber, a ring shaped member, connecting the vapor chamber, with the condensing chamber electrodes led in the vacuum vessel through the ring shaped member and arranged in a circle.

3. In metal vapor apparatus, the combination, of a vapor chamber, a condensing chamber, a ring shaped member rigidly connected with the condensing chamber and adapted to be detachably connected with the vapor chamber, and electrodes supported by and led in through the ring shaped member.

4. In metal vapor apparatus the combination, of a vapor chamber, a condensing

chamber, a cover having an orifice which communicates with the upper condensing chamber, said orifice being widened at its upper part so as to receive the lower extremity of the condensing chamber, the said cover also being detachably connected with the vapor chamber, and electrodes arranged in a circle and led in through the said cover.

5. In metal vapor apparatus, the combination, of a vapor chamber, a condensing chamber, an inclined ring shaped member, serving to connect the vapor chamber with the condensing chamber and electrodes arranged in a circle and passing through the ring-shaped member.

6. In metal vapor apparatus, the combination, of a vapor chamber, a condensing chamber, a ring shaped member adapted to connect said chambers, anodes arranged in a circle and passing through the ring, and cooling cylinders surrounding both the vapor chamber and the condensing chamber and communicating with each other by means of tubular connections.

7. In metal vapor apparatus, the combination, of a vapor chamber, a condensing chamber, a ring shaped member connecting the vapor chamber and the condensing chamber, electrodes arranged in a circle and passing through the said ring member, and a screen for causing the anode streams to be directed immediately to the cathode.

8. A device of the character described including a vapor chamber, a condensing chamber detachably connected with the said vapor chamber, anodes arranged to project into said vapor chamber, a cathode also arranged in said vapor chamber, and deflecting means for directing vapors generated by the anodes to the said cathode.

9. A device of the character described including a vapor chamber, a condensing chamber, and sealed coupling means for detachably connecting said chambers, anodes arranged in said coupling means and adapted to project into the vapor chamber, a cathode located in said vapor chamber, and means for directing vapors generated by the anodes immediately to the said cathode.

In testimony whereof I have affixed my signature in presence of two witnesses.

BÉLA SCHAEFER.
